UNITED STATES PATENT OFFICE.

HARRY BENJAMIN GOLDMAN, OF PITTSBURGH, PENNSYLVANIA.

ELECTRICAL CONTROL SYSTEM.

Application filed April 4, 1925. Serial No. 20,787.

My invention relates broadly to elevator control systems, and more particularly to electrical circuits and apparatus for increasing the safety and convenience of operation of elevator systems.

One of the objects of my invention is to provide a circuit arrangement for elevator systems operative with either an alternating current or a direct current source in which 10 a plurality of separate pieces of apparatus are employed to check one against another and cooperate in such manner that the elevator may be operated with a high degree of safety at all times independent of the personal equation of the operator.

Still another object of my invention is to provide a circuit arrangement for elevator systems in which a plurality of protective and corrective instruments are provided through 20 which the electrical circuits must be completed before the elevator can be operated up or down the elevator shaft.

Still another object of my invention is to reduce the complications of the controls in 25 the car switch, thereby securing reliability of the operation and reduction in the maintenance and initial manufacturing expense of the apparatus.

Still another object of my invention is to 30 provide a circuit arrangement which avoids the undesirable operation of reverse switches when the car is moving in either up or down direction. That is to say, I provide means whereby the car must be brought to a condition 35 of rest before operation of the reverse switches, thereby relieving undesirable strain on the operating motor and other mechanical parts of the system.

Still another object of my invention is to 40 provide a system wherein the same wires installed for operation of the elevator system may be utilized for the operation of the corrective and protective devices of my system without the requirement of additional switch 45 contacts in the car switch.

Still another object of my invention is to 50 provide non-plugging means in an elevator system for preventing abuse due to inching, that is, the tendency of the car to stop in a place out of level with the level of a floor and then be moved towards the floor in a series of undesirable jolts, this being avoided in my system by introducing a time lag in the operation of the circuits whereby the ele-

vator equipment comes to a positive rest before being again placed in operation for moving the elevator to an exact floor level. 55

My invention further resides in the construction of timing apparatus, sequence relays, a centrifugal governor, contingent limit 60 switch, and door contacts for connection in the elevator control circuits, as will be more fully hereinafter described.

My invention provides means whereby the operator of the elevator is prevented from controlling the elevator merely by operation of the elevator door. It is the dangerous practice of the elevator operator, when at rest adjacent the floor level, to admit passengers to the car with the door opened and the car switch in "On" position and then starting the car by closing the elevator door and completing the door contact. This is an undesirable and exceedingly dangerous method of operation. My invention provides 70 means for eliminating this danger by requiring a series of operations where the door contacts are first closed and then the switch thrown to the "On" position before the car 75 can be made to function. 80

In my system the operating coils are arranged in such relationship in the circuits that contacts are closed on the accelerating movement and the reverse movement with the same values of current through the 85 switches whereby the contact pressure is always the same. Heretofore the reverse and relay systems used in elevator control circuits have had to be constructed very carefully and the balancing resistances in the circuit graduated with extreme accuracy to insure operation. The spring tension on all the switches 90 has had to be accurately set and accurately maintained at a certain tension. If these details are not accurately adjusted, the current through the operating coils when reduced to a 95 very low value makes it difficult to keep the switches from unsealing, reducing the pressure on the contacts which are controlled by the several armatures and giving rise to the 100 tendency of broken circuits when it is necessary that the circuits be maintained. On the other hand, if the current through the opening coils is not reduced to a low value but is kept fairly high then the switches may 105 close whether the control resistance is introduced or removed from the circuit. In my system I provide a contact A on the accelerat-

ing movement which is wired in the relay circuit, which contact must be closed in order to close the contact relay so that the current in the operating coils can remain constant 5 and thus the contact pressure may be maintained constant even though the voltage may vary widely and the adjustment of the spring tensions on the armatures may be different, thereby insuring more positive operation of 10 the system.

Furthermore, where it is desirable to use this protective feature with slip ring motors in A. C. systems, to insure the motor always starting with full rotor resistance in circuit, 15 this protection can be secured with my circuit and not with circuits heretofore known in the art for the reason that in my system selected values of resistance proportioned to the remainder of the system are utilized. If 20 enough resistance were used in series with an alternating current switch to prevent the closing thereof—the resistance being in circuit while the switch is opened—the switch would probably fail to remain in closed position 25 even though it might trip instantaneously. A. C. switches are very sensitive to changes of current so that the insertion of a misproportioned value of resistance might result in loud humming and possible opening 30 of the switch control circuit.

In order to obtain automatic reset of the overload relay, where one is used, from the car switch handle, it is the practice of the prior art to make a double coil relay, one coil 35 of heavy wire for insertion in the main circuit and the other a shunt coil for placing across the line. The shunt coil of the ordinary overload relay is placed over the series coil and has a resistance in series with it so 40 adjusted that the current through the shunt holding coil is low enough to not pull the plunger of the relay up, but will hold it there after the series coil pulls it up into the shunt coil's magnetic circuit. If it is desired to re- 45 set the overload relay the circuit to the shunt coil must be broken to allow the plunger to fall into its normal position. In the event an overload has caused the plunger to be tripped or pulled up, thus opening the control cir- 50 cuit, the car switch must be returned to center in order to break the shunt coil holding circuit and release the plunger. This means usually an extra wire or wires to the car switch and extra fingers in the car switch. 55 With the circuit of my invention it is not necessary to have either the shunt holding coil, its resistance, any extra wires to the car switch, or extra fingers in the car switch. This enables me to simplify the construction 60 of the controls, reducing their cost and increasing the reliability thereof.

I provide a sequence relay whose two normally open contacts in the control circuits break both the "Up" and "Down" reverse 65 switch circuits, thus assuring that no combi-

nation of shorts and grounds in the reverse switch circuits will cause the reverse switches to remain closed if the sequence relay opens. It will be noted that the sequence relays employed in my invention are wired so as to use 70 the same conductors as are already provided for the reverse switch circuits so that the circuits function for two purposes, that is, in energizing the reverse switch circuits and in obtaining the sequence operation. 75

Heretofore in the art considerable abuse has been given to the elevator equipment due to reversing the mechanism before it has come to a stop and due to the sudden starting and stopping the equipment successively 80 in "inching" to a floor level. In prior systems if the car were going up to a floor and the operator stopped below the floor, say ten inches, considerable strain on the elevator mechanism has been necessary in successively 85 applying the operating current in the control circuits for moving the car through a series of infinitesimal distances to the floor level. In my system the car is definitely stopped before the operator can move up or down the shaft or in the same direction. A very valuable feature with this device is that it is adjustable as to how long an interval must elapse before the car can be moved again, it being possible to make the operator wait fifteen 90 seconds, if desired, or adjustment can be made to accurately coincide with the exact stop of the elevator, allowing for drift and loading. Thus the stopping equipment, including dynamic braking, mechanical, elec- 95 tric band, or jaw brakes, are brought to a condition of rest before the system is reversed or started, even in the same direction, thereby eliminating undesirable wear on the parts. 100

The timing device employed in my invention may be either mechanically actuated by plungers, electromagnetically operated by the controller magnets or by the brake movement, or it may be electrically operated by a magnet placed in parallel with the shunt brake. The timing may be regulated by means of a dash pot over a time interval of fifteen seconds more or less as may be necessary in the particular system. 105

A centrifugal governor is employed in the system for obtaining protection against overspeeding into the terminals. The centrifugal governor contacts are placed in parallel with the contingent limit switch which is mounted on the car, insuring that the car must be on slow speed when approaching either terminal or car will stop. This avoids the occasion of serious accidents which have occurred due to cars crashing into terminals at high speeds. The centrifugal type of governor and the contingent limit switch connected in the circuit as I have illustrated prevent accidents such as these are independent of the derangement of the equipment or the operator's forgetfulness. The operation of the 110 115 120 125 130

contingent limit switch forces all apparatus to be returned to the "Off" position after functioning, thus preventing "telegraphing" of switches if the control switch is held in the 5 "On" position after the contingent circuit has been opened.

I have improved the door contacts used in the system of my invention. Heretofore in an installation of say twenty floors served 10 by an elevator each floor has been equipped with a door switch. In the event that one or more of the switches failed to "make" contact, each of the switches must be eventually inspected to determine whether or not the 15 contacts are in proper order. This has necessitated the removal of sheet metal covers from each of the switches until the defective contact has been found. Often every cover may be removed before the defect is 20 discovered, which covers must be subsequently replaced. By my present construction the contacts for the door switches are plainly visible at all times through an aperture closed by clear mica or other transparent 25 material in the switch cover. This allows the ready inspection of the switch contacts without removal of the box covers and at the same time maintains the switch bug and dust proof.

30 My invention will be more clearly understood by reference to the following specification and accompanying drawings, wherein:

Figure 1 is a diagrammatic view showing the arrangement of the elevator equipment 35 and the electrical connections thereon for performing the objects of the invention, with modified circuit connections illustrated in dotted lines; Fig. 2 is a side elevation partially in cross section showing the construction of the timing relay for the non-plugging device; Fig. 3 is a front elevation of the timing relay illustrated in Fig. 2; Fig. 4 is a fragmentary view showing an electromagnetic operating means for the timing relay; Fig. 5 is a front view of the centrifugal 45 governor used in my elevator system with the cover of the casing removed to show the interior parts. Fig. 6 is a side elevation of the governor construction; Fig. 7 is a front view 50 of the sequence relay which I employ in the circuit arrangement of my invention; and Fig. 8 is a side view of the sequence relay illustrated in Fig. 7.

Referring more particularly to Fig. 1 of 55 the drawings the circuit may be traced from the line L1+— through "P" resistance, it being assumed that car switch 30 is in "off" position, through control fuse F, through "OS" or overspeed governor contacts, 60 through one side of "final up, final down" and car safety switch contacts X4—X3—X2—X1—X. Here it will be observed that L1+ after going through these contacts, feeds coil on F. B. switch and to one side of the circuit 65 for U1, U2 and D1 and D2. The ends of U1

and U2, and D1 and D2, go directly to the top stationary contacts 78 and 79 on the double pole-double throw sequence relay SR.

Assume now that a circuit is closed through door contacts D, the contacts A of the interlock on the acceleration movement, the contacts of the governor G, the B contacts on the timing relay, the overload relay contacts C, through the circuit passing through the over-speed governor switch OS and through 70 the circuit containing the final limit contacts N1—N2, then the four pole double throw relay SR will be closed. The car switch 30 must be in center to allow relay SR to go in, even if everything is closed after car switch is 75 thrown to "on" position. In other words, all of the above contacts must be closed first, to bring the relay SR in when car switch 30 is in "off" position. If car switch 30 is thrown to "on" position first and then final contacts 80 closed, it is necessary to return car switch to "off" position to allow relay SR to come in, before car switch 30 is thrown to "on" position. That is to say, it is necessary that the relay 85 coil 34 be first energized by the closing of the door contacts D and the contacts in the circuit between line L1— and L2— as follows: From line L1— through resistance P through fuse F, through contacts X4 on the over-speed governor switch OS, through the final 90 limit up switch X3, the final limit down switch X2 through the car safety switch contacts X1—X, through conductor R interlock fingers 55 or 56, through contingent limit switch 31, contact C, door contacts D, sequence relay resistance 33, sequence relay coil 34, contacts N—N1, on final limit down switch, contacts N1—N2 on final limit up switch fuse 35 and line L2—. This arrangement thereby avoids the danger of accidents 100 by preventing the starting of the elevator or by the functioning of the sequence relay until the door contacts are initially closed.

The "P" resistance as shown is not an essential part of my system. I prefer to connect the points 90 and 91 in the circuit positively by a shunt connection thereacross. The points 90 and 91 connect across the contact W of the accelerating movement. The reason for an interlock on 57 is to provide for a contingency where a direct current motor may be thrown on the line with all its armatures cut out, resulting in a dead short circuit. As the motor armature resistance limits the "initial" or "starting" current to 110 a definite value until the motor accelerates, then the starting resistance may be gradually short circuited, as the counter electro motive force, generated by the rotating armature 115 builds up, acting to keep the line current normal. The interlock on "57" must be closed before the direction switches or "FB" can close.

When using the "P" resistance it is necessary to build the switches very carefully, and 120

adjust the "P" resistance accurately. However, with a shunt circuit across the contacts W these refinements are not required.

With car switch 30 in center the closing circuit for relay SR can be traced as follows: Trace L1+ through or over bridge of "P" resistance, through fuse F, through X4—X3—X2—X1—X, over "R", through "A", through "B", through contingent limit switch 31, which in "stopped" position of equipment is "shorted" by governor contacts 32, through overload relay contacts C, through door contacts D, through sequence relay coil resistance 33, through sequence relay coil 34 to "N"—"N2", through fuse 35, to L2.

It will be noted that sequence relay coil 34 is in series across the line with the sequence relay resistance 33. The ohmic value of the resistance 33 is properly proportioned with that of the coil 34 so that the low current which flows in the circuit, plus a large number of turns on the relay coil 34, provides ample pulling capacity to close the relay armature of relay SR. The sequence relay resistance is always high enough so that it can be placed across the supply lines continuously, by itself, without injury.

With the relay SR closed, the car switch 30 is thrown for example, to the "Up" position and the rest of the circuits may be traced.

Starting from -L2, through "fuse" 35, through N2—N1—N in car switch 30, current now goes two ways, through contact "2" to "Up" stop switch 36, through finger 37 on relay to stationary stud on relay 38, to "U2"—to "U1", through "F. B." coil, through "X"—X1—X2—X3—X4, through fuse F, through "P" or over bridge on "P", to the line L1+. This brings in "Up" direction switch which energizes the armature circuit, and "F. B.", which "shorts" resistance in shunt field out thus giving full field strength for starting and also energizing the brake coil. As soon as the "F. B." switch goes in, the shunt brake coil is energized. Across the brake coil is placed the coil on the timing device, solenoid 39 in Fig. 4. This coil causes the armature 40 to project the plunger 41 of the timing device B, thus breaking the circuit of the relay coil at "B" by the removal of the bridging member 42 from between the spring pressed fingers 43 and 44. The timing device includes a dashpot 45 with a reciprocal piston 46 therein with a time adjusting means 47 carried thereby to control the operating period of the down stroke. In the construction illustrated, I am able to introduce a time period of from zero to fifteen seconds. The initial adjustment when once made remains in adjustment for indefinite periods. The piston 46 is connected by piston rod 48 with a bell crank 49 pivoted at 50. An adjustable weight 51 is provided on one

arm of the bell crank 49. The lower arm 52 of the bell crank is connected at 53 with the plunger 41 in such manner that the position of the plunger may be controlled by the abutment of a rod 54 actuated by either the reverse switches, the brake magnet, or by an individual magnet such as the magnet 39 in Fig. 4. The timing device B forms the "non-plugging" control for the elevator system and prevents automatically the reversal and "inching" of the motor until the entire elevator equipment has come to a full stop. Most elevator motor armature failures are caused by two things—oil and dirt collecting on the armature causing deterioration of the insulation and abnormal "plugging" current. By far the greater number of elevator motor troubles as well as mechanical troubles are caused by "plugging." "Plugging" is the act of going from full speed in one direction to full speed in the other direction without first coming to a full stop before reversing.

The device of my invention automatically prevents reversal of the motor until the entire equipment has come to a full stop.

The plunger 41 may be mechanically actuated as heretofore described in lieu of the electrical method illustrated in Fig. 4 by the reciprocatory movement of the plunger 54 as illustrated in Figs. 1 and 2.

The setting of the accelerating dashpot 45 and timing device 47 controls the period of opening and closing of the relay circuit. Then, as the equipment comes up to speed, the short circuit across the contingent limit switch 31 caused by the governor contacts 32 is removed.

However, the sequence relay SR does not fall out, because on the bottom of the reverse switches are normally open interlock fingers 55 and 56 which are closed, as the reverse switch closes, thus creating a circuit from L1+ through or over bridge of P resistance, through fuse F, through X4—X3—X2—X1—X, over R through interlock on bottom of U switch 55 down through contingent limit contacts 31, back through overload relay contacts C, through door contacts D, through resistance 33, through coil 34, back through N—N1—N2— through fuse 35 to -L2, thus shorting contacts on A and B.

The acceleration circuit does not require description here other than to point out that the A contact is opened by the accelerating movement. The A contacts serve as a protection for the armature of the driving motor so that the motor cannot be started unless all of the armature resistance is in the circuit. The contacts A are mounted on the accelerating device and are closed when the accelerating fingers are in open position.

With the circuits set as described the elevator will be running up the shaft at full speed. The speed governor G on the motor

has by centrifugal force, opened its contacts 32. Thus it can be seen that if the contingent limit switch contacts 31 were to open, the SR coil circuit 34 would be broken and the car would stop. However, in ordinary operation, as the car approaches either terminal it is slowed down by the opening of either the up slowdown switch or the down slowdown switch, thus allowing the governor contacts

10 G to close, and short the contingent limit switch 31 before it is opened. However, if the car failed to slowdown before the contingent limit switch 31 is opened, then the governor contacts 32 fail to short the contingent limit contacts 31 and when the contingent limit is opened the car stops since the coil circuit 34 is broken.

Assume that the car is slowing down correctly at terminals the action of the A contact 20 may be observed. As soon as the accelerating movement 57 begins to operate the A contact is opened and if it should for any reason, fail to close when car switch handle 30 is returned to off and then to on positions control will not function. The accelerating movement 57 operates to cut out armature resistance in accordance with the speed control of the elevator motor.

The timing device B having actuating 30 winding 39 purposely slows up its making contact at 42, as the coil is de-energized. This time lag can be any period desired but is usually just enough to force the operator to allow the equipment to come to rest, before throwing car switch 30 in either up or down direction, or in the same direction.

Assuming that equipment is at rest, with car switch 30 in center, and one of door contacts D open, with every other contact normal. 40 Presume that the operator throws car switch 30 to up position and then closes door contact D, the car will not start or control function. The reason for this will be observed by tracing the circuit as follows:

45 With the car switch 30 in the up position and a door contact D open, the circuit can be traced starting with -L2, through N2-N1-N to car switch 30, through up stop switch 36, to contact 37 on relay SR, to bottom stationary contact 63 on relay, up through bottom fingers 62 on relay, through resistance 33, through door contacts D, through contacts C on overload relay, through contingent limit switch contacts 31, through B, through A to

50 R, through X-X1-X2-X3-X4, through fuse F to +L1, thus putting resistance 33 directly across the line, and shunting the sequence relay coil 34. Therefore, as long as the car switch 30 is held in the on position, if 55 the final contact of any of the devices is made after car switch is thrown to on position, the resistance 33 remains across the supply lines and the relay remains in the normally open position, with its coil 34 shorted or shunted.

60 65 However, if the car switch is brought to the

off position, then relay will close and establish the proper connections for going in the desired direction. This is so because the current then flows from -L2, through fuse 35, through N2-N1-N, through coil 34, 70 through resistance 33 and so through rest of devices to +L1. Since the current flows now through the coil 34, the relay SR closes, thus opening bottom contacts 61 and 63.

The normal and desired operation of this 75 relay is to force the operator to first close the doors to which the door contact D is attached and then move the lever 30 to the on position. If it is done in any other way, the car will not move. This does away with the dangerous 80 practice of an operator standing at a floor, with the door open, admitting passengers with the car switch in the on position, then closing the door and starting the elevator by means of the door contact. This is done 85 extensively where no relay is employed to prevent such action.

The non-plugging feature introduces a delay into the circuit, such delay being pre-determined and adjusted to coincide with the 90 exact stoppage of the equipment. This makes it impossible to either reverse the equipment or go in the same direction, or start at all, until the contact, shown at B is closed. If 95 the car switch 30 was to be moved before contact B closes, the control would not function, independent of the fact that the car switch may be held in the "on" position indefinitely. The opening of any of the devices in the N2 circuit or the X4 circuit gives the same results 100 as any opening in the relay circuit proper.

It will be noted that when contacts on X4-X3-X2-X1-X are opened or contacts on N2-N1-N are opened, they will break a somewhat larger current than will the contacts in circuit with the coil 34. This is due to the fact that these contacts feed, in addition to the relay circuit, the F. B. and reverse switch coils, U1-U2-D1-D2. This does not offer serious difficulty however for the reason that these contacts which handle the somewhat larger current are very rarely broken and the current handled is not, ordinarily, over one-half to three-fourths of an ampere. Since these contacts are in a fairly large switch, the current can usually be handled 110 fairly well, especially with the infrequent operation.

115 My system has the great advantage, however, of maintaining the current low across the door contact switches D. These switches are usually installed where space is at a premium. The switches are normally very small and the contacts are necessarily crowded. The spacing between contacts and between contacts and ground potential of the elevator shaft is very small and this, coupled with frequent operation, makes it of vital importance to keep the current as low as possible, otherwise, if the contact should be 120 125 130

opened with the car switch in on position, the arc may be, and often is, large enough to cause a jump to ground or hang on across the contacts. Either condition is liable to cause operating trouble. In my arrangement of circuits and relay this difficulty is eliminated.

I have shown in Figs. 5 and 6 the details of construction of the governor wherein reference character 65 designates the driving motor 10 armature shaft carrying a central bolt 66 on which the elements of the governor are mounted. The entire governor is housed within a casing 67 including the frame 68, whose position may be adjusted by set screw 69. The 15 governor element, which may be balanced with shot, is indicated by reference character 70 secured to an actuating rod 71 adapted to move radially against the action of spring 72 operating the bell crank 73 to move the slide- 20 ble collar 74. The position of the collar governs the operation of the contacting device 75 cooperating with the fixed contact 76 forming the terminals 32 as shown in Fig. 1. The contacts may be mounted upon an insulating 25 block 77 within the governor housing in such position that the moving contacts 75 may be readily pressed thereagainst. The centrifugal relay may be used with either alternating current or direct current and is normally set to open at a car speed of from forty 30 to seventy feet per minute. It is frequently mounted on the motor or safety governor.

In Figs. 7 and 8 the construction of the sequence relay has been more clearly illustrated 35 with the lower contacts 63 and 61 and the upper contacts 78 and 79. The resistance unit 33 is mounted on the rear of the panel 80 which supports the relay. The insulated plate 81 carries the contact fingers 37, 81, 82 and 83, the latter comprising contacts 62 the 40 plate being pivotally mounted as represented at 84. As heretofore explained, the relay does not break heavy current, thus giving indefinite life to the contacts as they are subjected to mechanical wear only. The spring tension 85 enables the relay to operate quickly without lag.

As heretofore noted the door contacts D 45 are housed in such manner that they may be readily observed without removing the cover from the box.

While I have described this invention with 50 relation to elevator equipment, it will be apparent that the principle of the invention 55 may be embodied in protective systems such as a lock system for automobiles whereby the opening of the door of the car actuates a contact which will lock up the entire system. This equipment upon an automobile is particularly desirable in a closed car inasmuch as 60 it may be arranged so that the car cannot be started until all the doors are closed and locked. This prevents doors from being torn off by starting and tampering.

65 It will be understood that other modifica-

tions may be made in my invention and that I intend no limitations upon the invention other than are imposed by the scope of the appended claims.

What I claim and desire to secure by Letters Patent of the United States is as follows:

1. An elevator system comprising in combination an elevator, driving apparatus for said elevator, a controller for actuating said driving apparatus, a sequence relay in circuit 75 with said controller, and circuit closing means adapted to introduce a time lag in the operation of said sequence relay whereby said controller is prevented from reversing the direction of movement of said elevator until said elevator has been brought to a condition of rest.

2. An elevator system comprising in combination an elevator, driving apparatus, a controller for actuating said elevator, circuit connections including a source of energy and said driving apparatus, door contacts interposed in said circuit, means for controlling the opening and closing of said circuit over variably adjustable time periods, and means whereby said door contacts must be closed prior to the actuation of said controller before said elevator can be placed in motion.

3. An elevator system having a plurality of control circuits, an elevator, driving apparatus for said elevator, a controller for governing the movement of said elevator in either of two directions, a door contact in one of said control circuits, means for controlling the opening and closing of said circuits over variably adjustable time periods, and means whereby said door contacts must be initially closed prior to the operation of said controller before said elevator may be moved in either direction.

4. An elevator system having a plurality of control circuits, an elevator, driving apparatus for said elevator, a controller for governing the movement of said elevator in either of two directions, a door contact in one of said control circuits, a sequence relay in each of said control circuits, means for controlling the opening and closing of said circuits over variably adjustable time periods, and means whereby said sequence relay may be closed by sequentially closing said door contacts and next actuating said controller to move said elevator in either direction.

5. An elevator system having a plurality of control circuits, an elevator, driving apparatus for said elevator, a controller for governing the movement of said elevator in either of two directions, a door contact or multiple number of door contacts in one of said control circuits, a sequence relay common to all of said control circuits, a coil arranged to magnetically actuate said relay, a resistance, means for controlling the opening and closing of said circuits over variably adjustable time periods, and circuit connections whereby said coil is

shunted by said resistance when said controller is actuated prior to the closing of said door contact and said coil placed in series with said resistance when said door contact is closed prior to the actuation of said controller.

6. An elevator system having a plurality of control circuits, an elevator, driving apparatus for said elevator, a controller for governing the movement of said elevator in either of two directions, a door contact in one of said control circuits, a sequence relay common to said circuits, a timing relay in said door contact circuit and means whereby said driving apparatus may be actuated when said door contacts are first closed followed by operation of said controller, said timing relay being actuated at each reversal of said controller for bringing said driving means to a condition of rest intermediate a change in direction of movement of said elevator.

7. An elevator system having a plurality of control circuits, an elevator, driving apparatus for said elevator, a controller for governing the movement of said elevator in either of two directions, a door contact in one of said control circuits, a sequence relay common to said control circuits, means in one of said control circuits for interrupting the energy supply system simultaneously with each reversal of the controller over a period of time for bringing said driving apparatus to a condition of rest prior to the next impression of the energy supply upon the control circuit, said controller being arranged to actuate said driving apparatus only when the actuation of said controller is subsequent to the closing of said door contact for moving said elevator in either direction.

In testimony whereof I affix my signature.

HARRY BENJAMIN GOLDMAN.
